UNITED STATES PATENT OFFICE.

LEWIS NELSON SOPER, OF GUELPH, ONTARIO, CANADA.

UPRIGHT-PIANO ACTION.

1,000,762.

Specification of Letters Patent. Patented Aug. 15, 1911.

Application filed January 8, 1911. Serial No. 600,575.

To all whom it may concern:

Be it known that I, LEWIS NELSON SOPER, a subject of the King of Great Britain, residing at Guelph, in the county of Wellington, Province of Ontario, and Dominion of Canada, have invented certain new and useful Improvements in Upright-Piano Actions, of which the following is a specification, reference being had therein to the accompanying drawing.

10 This invention relates to upright piano actions of that type disclosed in United States Letters Patent No. 924,394, granted to me June 8, 1909.

15 The invention has for one of its objects to provide a piano action which possesses a perceptibly lighter touch than is possible with actions heretofore known to the trade, this latter touch being accomplished through 20 the agency of a novel spring arranged between the jack and hammer, whereby the hammer is carried to the striking point with less weight being brought to bear on the key.

25 Another object of the invention is the employment of a supplemental cushion on the hammer butt so arranged as to come into contact with the hammer spring at a time when the hammer is about three-eighths

30 of an inch, more or less, from the string, so that during the final part of the striking movement, the hammer spring is placed under a decided tension which insures a quick return of the hammer to check position and 35 at the same time the re-bound of the hammer from the string causes the repeating spring between the jack and hammer to insure a positive repeating and a more rapid movement than has been heretofore attained.

40 With these objects in view and others, as will appear as the description proceeds, the invention comprises the various novel features of construction and arrangement of parts which will be more fully described 45 hereinafter and set forth with particularity in the claims appended hereto.

45 In the accompanying drawing, which illustrates one embodiment of the invention, Figure 1 is a vertical section of an upright piano action with the parts in normal position. Fig. 2 is a similar view showing the position assumed immediately prior to the hammer striking the string. Fig. 3 is a similar view of the parts adjacent the hammer butt and jack showing the parts in the position they assume when the hammer is at

check. Fig. 4 is a detail view of the repeating spring. Fig. 5 is a modified arrangement of the spring.

Similar reference characters are employed 60 to designate corresponding parts throughout the views.

Referring to the drawing, 1 designates the jack; 2, the hammer butt; 3, the counter-check shank; 4, the counter-check; 5, the 65 check; 6, the hammer; 7, the hammer spring; and 8, the hammer spring seat on the butt 2; the said parts being arranged in the usual manner well known. A repeating spring A is employed between the jack and hammer 70 which, according to the present embodiment, consists of a wire of suitable gage formed with a coil 9 from which extend approximately right angularly disposed arms 10 and 11 which arms are normally without 75 tension. As shown in Fig. 4, these arms have laterally-extending members 12 and 13 that form pivots and connect the spring with the jack 1 and counter-check 4, respectively. The jack has a vertically disposed recess or 80 seat 14 in its top surface, and if desired, the jack may be formed with a lug 15 to better provide for the forming of the seat. This seat is lined by a doubled strip of felt 16 and the pivot 12 rests in the bottom or doubled 85 portion of this felt, as clearly shown. The upper pivot 13 passes laterally through an opening in the shank of the counter-check from one side so that the coiled portion 9 and arms 10 and 11 of the spring are disposed to one side of the vertical plane of the counter-check shank 3. A simple manner of attaching the upper arm 11 to the counter-check shank is to pass the pivot 13 through an opening 17. The ends 19 and 20 of the 90 pivots 12 and 13 are bent at an angle so as to prevent the spring from becoming detached from the jack and counter-check. By thus connecting the repeating spring A to the counter-check, an effective lifting action is produced on the hammer by a spring 95 when the key is depressed, and while the hammer is in check position, as shown in Fig. 3, the spring will be under stress and as a result the jack will be quickly pressed 100 downwardly when the pressure on the key is released, so as to be ready for another operation.

105 Although the point of connection between the repeating spring and counter-check is 110 at the inner end of the shank near the butt of the hammer, it is to be understood that

it can be connected with any desired part of the counter-check. Thus, by reference to the modification shown in Fig. 5, it will be observed that the spring is connected with 5 the head 4 on the outer end of the shank or counter-check proper. The pivot 13^a of the spring passes through a recess 17^a in which the lower upturned end of the leather strip or facing 18 of the counter-check is 10 inserted. The end of the strip does not extend fully into the recess 17^a so that in the space thereby provided the pivot 13^a can be accommodated. The use of the term counter-check in the claims is intended to apply to 15 the parts 3 and 4 considered as a unitary member of the hammer.

The rear face of the hammer butt is provided with a cushion 21 in the form of a block of felt or other material located adjacent 20 the upper rear corner of the butt in such a position that the hammer spring 7 will be engaged by the cushion during the last part of the movement of the hammer, whereby the hammer spring will be placed 25 under tension and effect a quick return of the hammer to check position after the string is struck. This supplemental cushion 21 is located a slight distance above the seat 6, where the free end of the hammer spring 30 7 engages the butt. With the improvements embodied in a piano action, as described and illustrated, the keys operate with a lighter touch, and positive repeating and a rapid movement are rendered possible.

35 From the foregoing description, taken in connection with the accompanying drawing, the advantages of the construction and of the method of operation will be readily apparent to those skilled in the art to which 40 the invention appertains, and while I have described the principle of operation of the invention, together with the apparatus which I now consider to be the best embodiment thereof, I desire to have it understood that the apparatus shown is merely 45 illustrative, and that such changes may be made when desired as are within the scope of the claims appended hereto.

Having thus described the invention, what 50 I claim as new, is:—

1. The combination of a pivoted jack having an opening parallel with the pivot on which it moves, a hammer butt, a counter-check on the hammer butt and having an 55 opening parallel with the pivot of the hammer butt, a repeating spring having means on its extremities for loosely engaging in the openings of the jack and counter-check to pivotally connect the spring with such 60 jack and counter-check.

2. The combination of a jack, a hammer butt, a counter-check, and a repeating spring consisting of angularly disposed arms resiliently connected, the free extremities of the 65 arm being bent laterally and pivotally con-

nected with the jack and counter-check respectively.

3. The combination of a jack having a downwardly-extending recess, a hammer butt, a counter-check, and a spring consisting of angularly-disposed yielding arms arranged with one arm engaged in the recess and the other arm pivotally connected with the counter-check. 70

4. The combination of a jack, a hammer butt, a counter-check, and a repeating spring disposed between the jack and counter-check and bodily movable, said spring consisting of angularly-disposed resiliently connected arms having their free extremities provided 80 with laterally-extending pivots connected with the jack and counter-check. 75

5. The combination of a jack having a downwardly-extending recess in its upper end, a hammer butt, a counter-check having an upwardly-extending recess in its bottom, and a spring having angularly-disposed arms provided with laterally-extending pivots at their free ends engaged respectively in the recesses of the jack and counter- 90 check. 85

6. The combination of a jack having a downwardly-extending recess in its upper end, a hammer butt, a counter-check having an upwardly-extending recess in its bottom, a spring having angularly-disposed arms provided with laterally-extending pivots at their free ends engaged respectively in the recesses of the jack and counter-check, and a facing strip on the counter-check having one 100 end seated in the recess of the latter to hold the spring attached to the counter-check. 95

7. The combination of a jack having a downwardly extending recess in its upper end, a hammer butt, a counter-check having an upwardly-extending recess in its bottom, a spring having angularly disposed arms provided with laterally-extending pivots at their free ends engaged respectively in the recesses of the jack and counter-check, and a doubled cushion strip lining the recess in the jack and forming a cushion seat for the pivot of the spring connected with the jack. 105 110

8. The combination of a jack having a downwardly-extending recess in its upper end, a hammer butt, a counter-check having an upwardly-extending recess in its bottom a spring having angularly-disposed arms provided with laterally-extending pivots at their free ends engaged respectively in the 120 recesses of the jack and counter-check, a facing strip on the counter-check having one end seated in the recess of the latter to hold the spring attached to the counter-check, and a double cushion strip lining the recess in the jack and forming a cushion seat for the pivot of the spring connected with the jack. 115 125

9. The combination of a hammer butt, a seat thereon, a hammer spring having its 130

free end at all times engaging the seat, and a cushion arranged on the hammer butt and spaced from the seat to engage the spring at a point between its anchor end and the 5 seat engaging portion for placing the spring under tension during the last part of the movement of the butt.

10. The combination of a pivoted hammer butt, a seat on the hammer above the pivot, 10 a hammer spring anchored at its upper end and having its lower free end permanently slidably engaging the seat irrespective of the position of the hammer butt, and a

cushion fastened to the butt above the seat to engage the spring at a point between its 15 anchored end and its seat-engaging portion and place the spring under tension during the final part of the movement of the hammer.

In testimony whereof I affix my signature 20 in presence of two witnesses.

LEWIS NELSON SOPER.
